Fig. 2.

UNITED STATES PATENT OFFICE

HENRY EGGERS, OF DENVER, COLORADO

CAR-OPERATED MECHANISM FOR OPENING AND CLOSING GARAGE DOORS

Application filed July 13, 1928. Serial No. 292,362.

My invention relates to improvements in car-operated mechanism for opening and closing garage doors.

The primary object of the invention is to provide mechanism connected with the doors of a garage and which is actuated by a roller which is mounted in the driveway leading to the garage, in line with the wheels on one side of an approaching car, whereby the said roller is engaged and rotated by a wheel of the car and the mechanism is thereby operated to open the said doors to admit the car, or to close the doors, after they have been manually opened to permit the car to be backed out of the garage.

Further, to provide a latch for the said doors which is connected with the door opening mechanism in such manner as to be withdrawn to release the doors immediately before they are pushed upon by the operating mechanism, whereby the doors are free to be swung outward, by the pushing action of the mechanism.

These and other objects which will hereinafter appear are accomplished by the mechanism illustrated in the accompanying drawings in which:—

Fig. 1 is a plan view, showing the door opening mechanism connected to a pair of doors, and the manner in which the mechanism is operated by one of the rear wheels of an automobile.

Fig. 2 is a vertical transverse sectional view through a garage, showing the manner of supporting the door opening mechanism, its connection with the doors, and the cables which connect the same with the operating roller in the driveway.

Fig. 3 is a vertical sectional view through the upper forward end portion of a garage, showing inside elevation, the slide bar, the slide thereon and the manner of its connection with the garage doors.

Fig. 4 is a front end view of the front supporting bracket for the slide bar.

Fig. 5 is a vertical longitudinal sectional view—enlarged—of the roller and its support, which is rotated by one of the rear wheels of a car to operate the door opening mechanism.

Fig. 6 is a transverse sectional view of the same, showing the cables which are wound or unwound upon the roller shaft, and which are connected with the door opening slide.

Fig. 7 is a plan view of a different form of cable-operating element from that shown in Figures 5 and 6.

Fig. 8 is a vertical sectional view through the same, and

Fig. 9 is an enlarged plan view of the latch and its operating means.

Referring to the accompanying drawings:

The numeral 1 designates the side walls of an ordinary garage, 2 the rafters and 3 the side members or casings of the doorway, to which are hinged a pair of doors 4 in the usual manner. To the rafters are secured depending brackets 5 and 6, the bracket 5 being near the doorway. These brackets may be of any suitable construction and they support the opposite ends of a slide bar 7, which is on a level with the upper end portions of the doors 4. Upon this bar is mounted a slide, comprising a horizontal plate 8 having a longitudinal guide 9 on its under side, through which the slide bar 7 passes, the said bar being substantially rectangular in cross section, and the said guide being of corresponding shape to prevent a turning movement of the slide upon the bar.

The slide is provided with two parallel longitudinal slots 10, in which are inserted the right-angled ends of a pair of rods 11, the opposite ends of which are pivotally mounted in bearing blocks 12, which are secured to the respective doors. Each rod 11 comprises two sections which are connected by a turn buckle 13, thus enabling the rods to be lengthened or shortened so as to give the proper opening and closing movements to the doors relative to the movement of the slide 8.

The front bracket 5, is provided with a horizontal side extension 14, upon which is mounted a pair of sheave wheels 15 and 16, and the rear bracket 6 is provided with similar side extensions 17 upon which is mounted a sheave wheel 18. One end of a cable 19 is secured to a lug 20 on the under side of the guide 9 of the slide plate 8, and at the for-

ward end thereof, and this cable passes forward and over the sheave wheel 15 and thence to and over a sheave wheel 15A, which is mounted in a bracket A on one side of the doorway, and at the upper end thereof. From the wheel 15A, the cable 19 passes down to and over a sheave wheel 15B and thence to and over a sheave wheel 15C, which is mounted at the rear end of an underground passage X, which extends from the entrance end of the garage, to a suitable point on the driveway, and is covered by plates X1, as clearly shown in Fig. 1. From the wheel 15C, the cable 19 passes to and is secured to the shaft B, of a roller C, the shaft B being mounted in depending bearings C1 on a horizontal plate C2, which rests upon suitable supports D, and on a level with the face of the driveway. The plate C2, is concaved, as shown, and is formed with an opening C3 through which the highest face portion of the roller C projects; the highest point of the roller being on a level with the face of the driveway. The ends of the roller C are beveled or tapered, so that the highest points of the said ends are on a level with the ends of the opening C3 through which said roller projects, as shown by Fig. 6. By this arrangement, the ends of the roller are protected, while the highest point of the roller is above the level of the opening in the plate but on the same level as the driveway, thus enabling the wheel of a car to engage the roller, although the roller does not project above the level of the driveway.

A second cable 21 is secured at one end to a lug 22 on the underside of the guide 9 and at the rear end thereof, and this cable passes over the sheave wheel 18 on the rear bracket 6, and thence to and over the sheave wheel 16 on the front bracket 5, and thence to and over a sheave wheel 21A which is mounted in the bracket A on the same shaft with the wheel 15A, and thence to and over a sheave wheel 21B, on the same shaft with the wheel 15B, and thence over a sheave wheel 21C at the rear end of the underground passage X, and thence to the shaft B of the roller C, to which it is secured, after being wound several times around the said shaft, and in an opposite direction to the cable 19.

From the foregoing description taken in connection with drawings, it will be seen that when the roller C is turned in the direction of the arrow,—see Fig. 5.—the cable 19 will be wound upon the shaft B while at the same time, the cable 21 will be unwound therefrom. The cable 19, draws upon the slide plate 8 and moves it forward on the slide bar 7, and the rods 11 are thus pushed forward, and swing the doors 4 open to the positions shown in dotted lines in Fig. 1.

As the rear ends of the rods 11 are mounted in the slots 10 in the slide plate, and are at

the forward ends of the slots when the plate is at its rearmost position, it will be seen that the said plate will be moved some distance forward before the rear ends of the slots engage the rods, and start the opening movements of the doors; and this inoperative movement of the slide is to permit the withdrawal of a latch 22, which normally secures the doors 4 in closed positions, before the doors start to open, as will now be described.

The latch 22 is slidably mounted in a guide 23 on one of the doors, and its forward end portion enters a keeper 24 on the other door, thus holding the doors in closed positions, as will be understood by reference to Fig. 9. The rear end of the latch is provided with a vertically disposed slot 25 through which passes the crank end 26 of a vertical rod 27, which is rotatably mounted in bearings 28 on the door to which the guide 23 is bolted. The upper end of the rod 27 terminates in a right angled lever arm 29, which extends rearwardly over and close to the sheave wheel 15. This wheel 15 is provided with a number of upwardly projecting pins 30, one of which will engage the end of the arm 29, when the wheel 15 is turned, and swing the same, thereby turning the rod 27, the crank end 26 of which will act to retract the latch 22. By providing the wheel 15 with a number of pins 30, some one of them will always be in position to engage the arm 29; and the end of this arm is beveled, as shown in Fig. 1, so that as the doors close, and the arm 29 passes over top of the wheel 15, it will be guided to one side of any pin that may chance to be directly in its path. The latch is normally held in closed relation by a coil spring 31 which surrounds the rod 27; one end of said spring being secured to the arm and the other end, to the door. When the opposing edges of the doors approach each other in closing, the beveled end of the latch will engage the edge of the opposite door whereby the latch will be moved inward; but when the doors are fully closed, the latch will be sprung into the keeper 24, by the spring 31, thus securing the doors in closed positions.

The mechanism is operated in the following manner:—As a car approaches the doors of the garage, the rear right wheel is caused to engage the roller C in the driveway, and as it engages the roller, it ceases to act in propelling the car, particularly, if the driveway inclines upwardly toward the doors. The propelling force is thus shifted to the left hand wheel; but, as the power required to propel the car by the left hand wheel is greater than that required to turn the roller C, by the right hand wheel, the differential will act to turn the right hand wheel, and the left hand wheel will cease to function. Thus the roller C will be turned in the direction of the arrow, as indicated in Fig. 5, and the cable 19 will be drawn upon and the slide plate 8 drawn for-

ward thereby. During the initial movement of the slide plate, the lever arm 29 is engaged by a pin 30 on the wheel 15, and the latch 22 is retracted, as previously described.

5 The ends of the rods 11 are then engaged by the ends of the slots 10 in the slide plate, and the doors are thereby swung open until they engage the stops 4A, and thus prevent further movement of the slide plate, and therefore, further rotation of the roller C. The car then passes into the garage, and the doors may be closed by pulling on the cable 21. The doors are opened manually in order to permit the car to be backed out of the 10 garage, and when the rear right wheel engages the roller C, the mechanism is thereby operated to close the doors. Cable 19 winds over the shaft B of the roller C, and the cable 21 winds under the said shaft, so that when one 15 cable is being wound upon the shaft, the other is unwinding therefrom. If desired, the face of the roller C may be concaved instead of flat, as shown in the drawings.

In Figures 7 and 8 is illustrated a turntable which can be employed in place of the roller C, and which is arranged as follows:— A suitable support 32 is provided upon which rests a circular horizontal base ring 33, having an elongated inner ring 34, which is connected to the outer ring by radial arms 35. Depending arms 36 extend from the elongated ring 34, and terminate in a circular plate 37, having an upwardly projecting circular lug 38, which is in line with the axial center of the base ring 33. The base ring has a ball race 39 provided with anti-friction balls, and upon the balls rests a turn table 40, having a circular groove 41 corresponding to the ball race. The turn table is provided with 20 a depending hub 42, the lower end of which fits over the circular lug 38, and is flanged, as shown at 43. The circumferential edge of the turn table is formed with a depending lip 43A, which surrounds the base ring and prevents lateral movement of the said turn table on the ring. The elongated ring 34 surrounds the hub 42, and bears against its forward half, and the remaining portion of the opening through this ring is of increased diameter, so as to permit the flange 43 on the hub of the turn table to be passed therethrough in placing the turn table on the base ring or removing it therefrom.

A single cable 44 may be employed, which is wound several times around the hub 42, so that when one lap of the cable, is wound upon the hub, the other lap will unwind therefrom. The turn table is operated by the wheel of a car, as in the case of the roller C, care being taken that the wheel engages the turn table on one side of its axial center.

Having described my invention, what I claim as new and desire to secure by Letters Patent, is:—

65 1. The combination with a pair of doors

and a driveway leading thereto, of a slidebar, a slide mounted on said slide bar, rods pivotally connected at their ends to said slide and said doors, a roller mounted in said driveway, having an extended axle, and adapted to be 70 rotated by the prolonged engagement therewith of a driven automobile wheel, cables secured at one end to said extended axle and oppositely wound thereon, and sheave wheels over which said cables pass, the opposite ends 75 of said cables being connected to said slide, so as to move the same in opposite directions, according to the direction of rotation of said roller, whereby said slide is caused either to push or pull upon said rods, thereby to open 80 or close said doors; a latch for fastening said doors in closed positions, and means operated by one of said sheave wheels for withdrawing the latch.

2. The combination with a pair of doors 85 and a driveway leading thereto; of a slide bar, a slide mounted thereon, rods pivotally connected at their ends to said slide and said doors, a roller mounted in the driveway having an extended axle and adapted to be driven 90 by the prolonged engagement therewith of a rotating automobile wheel, cables connected to opposite ends of said slide, their opposite ends being connected to and oppositely wound upon the said extended axle, and suitably positioned sheave wheels over which said cables pass, said cables being adapted to move said slide in opposite directions according to the direction of rotation of said roller, a latch 95 for normally securing said doors in closed positions, a rod rotatably secured upon one of said doors having a crank end connected to said latch and a right-angled upper end which extends over one of said sheave wheels, and a pin on said sheave wheel for engaging said right-angled upper end, thereby to turn said rod and slide, said latch to release said doors. 100

3. The combination with a pair of doors 105 and a driveway leading thereto; of a slide having parallel slots therein, rods pivotally connected at one end to said doors, their opposite ends terminating in right-angled portions which extend through the forward ends of said slots, a roller mounted in the driveway 110 having an extended axle, cables connected respectively to the front and rear ends of said slide, their opposite ends being connected to and oppositely wound upon said extended axle, and suitably positioned sheave wheels over which said cables pass; a latch for said doors, a rod rotatably secured to one of said doors, having a right-angled arm at its upper end which extends over one of said sheave wheels, its lower end terminating in a crank 115 portion which connects with said latch, and a pin on said sheave wheel for engaging said arm, said roller being rotated by the driven wheel of an automobile on said driveway, whereby one of said cables moves said slide 120 125 130

to cause said rods to open said doors, the initial movement of the slide permitting the said pin to turn the rotatable rod and slide the latch prior to the opening movement of the doors.

⁵ In testimony whereof, I affix my signature.

HENRY EGGER.
